STRAIGHT RAZOR HANDLE

James R. Stiltner, 10237 NE. Halsey,
Portland, Oreg. 97220

Filed Mar. 6, 1969, Ser. No. 16,091

Term of patent 14 years

Int. Cl. D28—03

U.S. Cl. D95—3

FIG. 1

FIG. 2

FIG. 3

FIG. 1 is a side elevational view of a straight razor handle showing my new design;

FIG. 2 is a top plan view; and

FIG. 3 is a bottom plan view.

I claim:

The ornamental design for a straight razor handle, as shown and described.
